UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

GOVERNING MECHANISM FOR TURBINES.

1,072,929.

Specification of Letters Patent.

Patented Sept. 9, 1913.

Application filed August 5, 1909, Serial No. 511,280. Renewed February 16, 1912. Serial No. 677,963.

To all whom it may concern:

Be it known that I, WILLIAM L. R. EMMET, a citizen of the United States, residing at Schenectady, county of Schenectady, State of New York, have invented certain new and useful Improvements in Governing Mechanisms for Turbines, of which the following is a specification.

My invention relates to the governing of turbines which receive and are driven by the exhaust steam from one or more high pressure reciprocating engines or other low pressure source of supply. In such an arrangement it is undesirable to permit the pressure of the steam entering the turbine to fall below atmospheric pressure because the air admitted to the system by leakage under such conditions will impair the vacuum due to the condenser which is connected 20 to the turbine.

The object of my invention is to provide a governing mechanism which will automatically regulate or shut off the supply of steam to the turbine when the pressure of 25 its source of supply falls below atmospheric pressure and which will, upon the restoration of the pressure of the source above that of the atmosphere, automatically operate to restore normal operation or admit steam 30 from said source to the turbine.

For a consideration of what I believe to be novel and my invention, attention is directed to the accompanying description and the claims appended thereto.

35 In the accompanying drawings which illustrate one of the embodiments of my invention, Figure 1 is a view in end elevation of a low pressure turbine equipped with my improved governing mechanism; Fig. 2 is 40 an enlarged view of the valve mechanism and the motor for actuating it; and Fig. 3 is a sectional view of a pressure responsive device which, under certain conditions, prevents the speed governor from operating.

45 I have shown my invention in connection with the governing mechanism for turbines patented to Oscar Junggren on June 23, 1908, Patent No. 891,342, since it is well adapted for the purpose, but my invention 50 is not limited to this particular type of governing mechanism as it is of wider application.

55 1 indicates a low pressure turbine of the Curtis multi-stage type, although turbines of other types may be governed by my im-

proved mechanism. Exhaust steam from a high pressure reciprocating engine or other source of low pressure supply is admitted to the turbine by the conduit 2 and, after acting on the stationary and movable buckets therein, passes to the condenser by the exhaust pipe 3. 4 indicates a speed governor which is driven by the main shaft of the turbine. This governor may be of any usual or well-known construction. The 60 movements of the governor due to a change in speed of the turbine shaft are imparted to the governor lever 5 which is pivoted at 6. Motion between the governor weights and the lever is imparted by the rod 7. The 65 admission of motive fluid to the turbine is controlled by the butterfly or throttle valve 8 shown in dotted lines in Fig. 2. This valve or regulator is actuated by a fluid pressure motor 9. The motor may be actuated by 70 steam, air or liquid under pressure. The movements of the motor piston are controlled by the pilot or balanced piston valve 10 which is provided with a stem 11. This stem is attached at its upper end to the lever 12 and the latter is connected by the link 13 to the governor lever 5. The relation of the parts is such that the free end of the lever 5 moves downward under conditions of increasing speed and upwardly under conditions of decreasing speed. The piston rod 14 of the motor is connected to a sliding cross-head 15. Attached to the cross-head is 75 a link 16 whose outer end is attached to the actuator 17 shown in dotted lines. The actuator 17 is loosely mounted on the spindle 18 of the butterfly valve or regulator. Keyed to the spindle 18 is a clevis 19. Pivotally supported by the clevis is a locking device 20 which is provided with a projection or finger 21 that enters a correspondingly shaped notch in the actuator. The extension spring 22 normally holds these parts in engagement. So long as the finger 21 is in engagement with the slot or notch in 80 the actuator, the movements of the motor piston to and fro will act to move the butterfly valve or regulator about its axis in a manner to increase or decrease the amount of steam supplied to the turbine, depending upon which way the piston moves. Loosely mounted on the hub of the clevis 85 is an arm 23 to the free end of which is attached a weight 24. This weight is normally restrained from acting by the latch 100 90 95 105 110

25 which is pivoted at 26 to some stationary part. Rigidly attached to the spindle 26 is an arm 27 that is connected by the rod 28 to a lever 29. The lever 29 normally 5 stands in the position shown and is actuated by the emergency governor 30 when the speed of the turbine exceeds the normal by a predetermined amount, as 10 per cent. for example. When the emergency governor 10 operates, it releases the weight arm 23 and as the latter moves about its axis, it strikes a roller 31 on the locking device carried by the clevis, which action withdraws the pin or projection 21 from the actuator. Continued 15 movement of the arm in a downward direction imparts a hammer-like blow to the clevis which swings the butterfly valve about its axis and causes the same to close. If it be desired to trip the valve by hand it can 20 be done by pulling the chain 32 which will trip the latch 25 and permit the weight to fall in the manner just described in connection with the emergency speed governor. It will thus be seen that the butterfly valve 25 or regulator performs two functions, *i. e.*, that of a throttle valve to regulate the admission of steam to the turbine, and that of a stop- or emergency valve to shut down the turbine quickly by cutting off its supply of 30 steam when the speed becomes excessive.

In order to prevent overtravel of the motor or "hunting," an anti-hunting device is provided. In the present illustration of my invention it comprises a bell-crank lever 35 which is supported by a pivot 36 carried by a fixed bracket or other support. One end of the lever is attached to the cross-head by the pivot 37 while the other end is connected by the link 38 to the 40 horizontal lever 12. The lever 12 is pivotally attached to the stem 11 of the pilot valve. Assuming that there is an increase in speed of the turbine, the free end of the governor lever 5 is moved downwardly and with it the rod 13 and right-hand end of lever 12, the pivot 39 acting as a fulcrum for said lever 12. This displaces the pilot valve and the motor piston starts moving toward the left, or in a direction to decrease 45 the opening of the valve or regulator 8. Just as soon as the piston starts moving the cross-head moves the upper end of the bell-crank lever to the left which raises the rod 38 and therefore the left-hand end of lever 12. While this latter operation is taking place the pivot 40 acts as a fulcrum for the lever 12. As a result the pilot valve 50 is ultimately restored to its initial or mid position where it closes the ports of the motor. In other words the anti-hunting or follow-up device anticipates the action of the governor which can only change its direction of movement when the speed 55 changes. Without a follow-up device the speed of the turbine under load changes 60

would surge to a greater or less extent above and below the desired speed.

In operating a low pressure turbine condensing it is undesirable to admit steam to the turbine at a pressure below that of the atmosphere on account of the fact that air will leak into the system through the joints in the low pressure piping and impair the vacuum. To prevent this I provide a pressure regulator which acts in a 70 manner to prevent the butterfly valve or other type of governing valve from admitting any steam through the conduit 2 so long as the pressure at the source of supply is below atmosphere and which permits the 80 valve to admit steam when the proper pressure conditions are restored.

The pressure regulator in the present embodiment of my invention is constructed as follows: Mounted on the guide for the 85 upper end of the pilot valve of the motor or other support is a frame 41 which supports a cup shaped casting 42. Covering the top of the casting is a diaphragm 43 which is held in place by a ring 44 that is 90 bolted to the part 42. One side of the diaphragm, in this case the upper, is exposed to atmospheric pressure and the other side, in this case the under, is exposed to the pressure of the steam exhausting from the 95 engine or that in the exhaust header which supplies steam to the conduit 2. This communication is established by the pipe 45 which may be connected at any convenient point in the piping system so long as it is 100 between the point of exhaust of the reciprocating engine and the butterfly valve. The under side of the diaphragm is attached to a rod 46 which passes through a suitable stuffing box 47. A compression spring 48 105 acts on the diaphragm against the pressure of the atmosphere and also assists in supporting the weight of the rod 46 and attached parts. The travel of the rod 46 due to the action of the diaphragm is sufficient 110 when the latter is fully depressed to move the pilot valve 10 to a position where it will admit fluid to the right hand end of the motor cylinder and cause the piston 115 therein to move to the left and close the butterfly valve or regulator. In order to accomplish this result the pressure regulator must overcome the effect of the speed governor 4 on the pilot valve. This can be 120 accomplished by making the diaphragm of sufficient area to exert a relatively large force on the stem 11 of the pilot valve. So long as the pressure conditions remain unchanged the diaphragm will prevent the speed governor from acting because it is 125 overloaded to such an extent that its force is insufficient to raise the pilot valve and the diaphragm against the atmospheric pressure on the latter. Just as soon, however, as the pressure of the exhaust from the en 130

gine increases to that of the atmosphere, the pressures on the opposite sides of the diaphragm will be balanced and the rod 46 will move upward assisted by the spring 5 thus removing the restraint on the speed governor and the latter will re-assume control and through it the motor will move the butterfly valve to a position where it will admit an amount of steam sufficient to 10 satisfy the load conditions of the turbine. It will thus be seen that the butterfly valve or regulator has an additional function to the two already specified, *i. e.*, that of shutting off the supply of steam to the turbine 15 without, however, disconnecting it from the actuating motor. As to the first two functions the regulator is responsive to speed changes and as to the last function, to pressure changes. It will also be noted that 20 the action of the emergency governor means on the butterfly valve or regulator is in no way affected by the diaphragm or pressure responsive means. The advantage of this resides in the fact that under no condition 25 can the turbine run away.

I have referred to the diaphragm as being subjected on one side to the pressure of the source of supply to the turbine and on the other side to atmospheric pressure. Under 30 certain conditions I may subject the diaphragm to a pressure above that of the atmosphere, which pressure acts in opposition to that of the source of supply. Such an arrangement will be useful where the pressure 35 of the source of supply from the engine or other apparatus is above atmosphere, and yet it is desired to prevent steam below the predetermined pressure from entering the turbine.

40 In accordance with the provisions of the patent statutes, I have described the principle of operation of my invention, together with the apparatus which I now consider to represent the best embodiment thereof; but 45 I desire to have it understood that the apparatus shown is only illustrative, and that the invention can be carried out by other means.

What I claim as new and desire to secure 50 by Letters Patent of the United States is,

1. A governing mechanism for a turbine including a regulator and a speed governor for controlling the action of the regulator, with a means responsive to the pressure of 55 the source of supply of the turbine which when said pressure falls below a certain value overpowers the governor and causes the regulator to close.

2. In a turbine governing mechanism, the 60 combination of a regulator, a governor means for varying the position of the regulator in accordance with load changes on the turbine, a second governor means for disconnecting the first from the regulator and closing the latter suddenly under condi-

tions of excess speed, and a pressure responsive device which under certain conditions assumes control of the regulator to the exclusion of the first governor means.

3. In a governing mechanism, the combination of a regulator, a motor for actuating it, a controller for the motor, a speed governor that actuates the controller, and a pressure responsive means which under certain conditions overpowers the governor and acting on the controller causes the motor to move the regulator. 70

4. In a governing mechanism, the combination of a regulator, a means including a speed governor for actuating the regulator in response to load changes, and a means subjected to the pressure of the source of supply on one side and to a predetermined pressure on the other, which under certain pressure conditions overpowers the governor 80 and moves the regulator. 85

5. In a governing mechanism, the combination of a regulator, a means including a speed governor for actuating the regulator in response to load changes, a diaphragm 90 subjected on one side to atmospheric pressure and on the other side to that of the source of supply of the apparatus being governed, and a means for transmitting the motion of the diaphragm to and overpowering the governor. 95

6. In a governing mechanism, the combination of a regulator, a motor for operating the regulator, a pilot valve for the motor, a speed governor controlling the action 100 of the pilot valve under normal conditions, and a pressure responsive device which under certain conditions takes the control of the pilot valve away from the governor and causes it to admit fluid to the motor in a 105 direction to close the regulator.

7. In a governing mechanism, the combination of a regulator, a motor for operating the regulator, a pilot valve for the motor, a speed governor controlling the 110 action of the pilot valve under normal conditions, a diaphragm exposed on one side to a predetermined pressure and on the other side to that of the source of supply, and a means for transmitting the movements of 115 the diaphragm to the pilot valve.

8. In a governing mechanism, the combination of a regulator, a speed governor which normally controls the action of the regulator, a second speed governor which 120 under abnormal speed conditions closes the valve suddenly and this irrespective of the first governor, and a means responsive to abnormal pressure conditions which closes the regulator and holds it closed until the 125 predetermined pressure conditions are re-established.

9. A governing mechanism for a turbine utilizing low-pressure steam from a suitable source of supply which includes a regulator 130

means and a speed governor mechanism for controlling the action of the regulator means, with a device responsive to the pressure of the steam, and means for transmitting the action of the device to affect the governor mechanism so that when the pressure of the low-pressure steam from said source of supply falls below a predetermined value said device assumes control of the regulator means to the exclusion of the speed governor mechanism.

10. In a governing mechanism for turbines utilizing steam from a suitable source of supply, the combination of a valve for regulating the admission of steam to the turbine, a speed governor, a motor for operating the valve, a pilot valve for the motor, a lever pivotally connected intermediate its ends to the stem of the pilot valve, a connection between the governor and one end of the lever, a connection between the other end of the lever and the movable member of the motor, and a device responsive to the pressure of the steam from said supply

which moves the pivotal connection between 25 the lever and the pilot valve stem independently of the governor when said pressure tends to fall below a predetermined value.

11. In a governing mechanism for turbines utilizing steam from a suitable source of supply, the combination of valve mechanism 30 for regulating the admission of steam from the source to the turbine, speed responsive means for controlling the valve mechanism, and a device responsive to the pressure of steam supply that is normally out of engagement with the speed responsive means but is automatically moved into engagement with said means to modify its action on the valve mechanism when the pressure falls 35 below a predetermined value.

In witness whereof, I have hereunto set my hand this 3rd day of August, 1909.

WILLIAM L. R. EMMET.
